UNITED STATES PATENT OFFICE.

WARD E. WRIGHT, OF CHICAGO, ILLINOIS, ASSIGNOR TO UNION SPECIAL MACHINE COMPANY, OF CHICAGO, ILLINOIS, A CORPORATION OF ILLINOIS.

FEEDING MECHANISM FOR SEWING-MACHINES.

1,136,749.

Specification of Letters Patent. Patented Apr. 20, 1915.

Application filed February 13, 1909. Serial No. 477,758.

To all whom it may concern:

Be it known that I, WARD E. WRIGHT, a citizen of the United States, residing at Chicago, in the county of Cook, State of Illinois, have invented certain new and useful Improvements in Feeding Mechanisms for Sewing-Machines, of which the following is a description, reference being had to the accompanying drawing, and to the letters and figures of reference marked thereon.

The invention relates to new and useful improvements in sewing machines, and more especially to the feeding mechanism of a sewing machine.

The invention is herein shown as especially adapted to sewing machines of the character which operate to full or gather a piece of fabric prior to stitching the same, or full or gather one piece of fabric relative to another and secure the same together.

When placing a binding strip or the like upon a knitted fabric, and more especially when binding across the wales of the knitted fabric, said knitted fabric is very apt to become stretched or distorted in the stitching operation. By my improved mechanism, the knit fabric may be fed slightly faster than the binding strip or non-elastic fabric, and thus overcome the tendency of the knitted fabric to stretch, so that the two pieces of fabric will be evenly and smoothly stitched together. It is sometimes desirable when stitching one piece of fabric to another of the above character, to cause the fulling action of the feeding mechanism to cease, as for example, when crossing stay strips or the like.

The present invention contemplates providing an auxiliary feeding mechanism which is normally inactive or ineffective, and which may, without stopping the machine, be thrown into operation so as to operate upon the fabric to perform a fulling or gathering action of the character above noted.

The invention consists in the parts, arrangements, and improvements hereinafter shown and described and pointed out in the appended claims.

In the drawings, which show one embodiment of the invention, by way of illustration,—Figure 1 is an end view of a sewing machine embodying my improvements, with the work support shown in dotted lines; Fig. 2 is a top plan view of the forward

end of the machine, with the work support removed, showing the main and auxiliary feeding mechanisms, and also the presser foot, the presser bar being sectioned; Fig. 3 is a detail view, partly in section, showing the feed operating mechanisms in side view, with the auxiliary feed in ineffective operating position; Fig. 4 is a similar view, showing the auxiliary feed dog in effective operating position; Fig. 5 is a detail view, showing the auxiliary feed operating mechanisms with the auxiliary feed dog in ineffective operating position; Fig. 6 is a view similar to Fig. 5, showing the auxiliary feed dog in effective operating position; Fig. 7 is a detail view, showing a binding strip being attached to the body fabric, and the position of the auxiliary feed dog relative to the presser foot and binder; Fig. 8 is a detail view, showing the bracket for guiding the movements of the auxiliary feed bar; Fig. 9 is a detail from the rear of the machine, showing the auxiliary feed-dog-controlling mechanism.

The needle 1 is carried by the needle bar 2, which reciprocates in the needle head in the usual manner.

Coöperating with the needle 1 is a looper 3, which, as herein shown, is a thread-carrying looper pivotally supported on the looper support 4, which is oscillated by means of an arm 5, to give the looper its needle-avoiding movements. The looper is oscillated into and out of the needle loop by a suitable link 6. The above parts are of the usual construction, and will not need further description.

The presser bar 7 carries a presser foot 8 at its lower end, which, as herein shown, is made in two parts 9 and 10. The part 10 is rigidly carried by the presser bar, while the part 9 is mounted so as to yield independently of the main part 10. The main feed dog 11 is carried by a feed bar 12, which rests on an eccentric 13, carried by the main shaft 14. Said feed bar 12 is provided with a bracket arm 15, which engages the under side of the eccentric, so that as the eccentric 13 is rotated, the feed bar 12 will be positively raised and lowered to bring the feed dog into contact with the material. The feed bar 12 at its rear end, has spaced arms 16, 17, which straddle a bar 18, carried at the upper end of a rocking frame 19. The spaced arms 16 and 17 are so disposed

that the feed bar 12 may slide back and forth on the bar 18, but receive no movement whatever from the bar 18. The rocking frame 19 is connected by the usual arm 20 with a second link 21, which in turn is pivoted to a crank arm 22, carried by the slotted disk 23 mounted on the forward end of the shaft 14. As the main shaft rotates, the rocking frame 19 will, therefore, be oscillated back and forth. Said rocking frame 19 carries a laterally extending bracket or arm 24, which is provided with a segmental slot 25.

The feed bar 12 carries a stud 26, to which 15 is pivoted a link 27. Said link at its other end is connected to a stud 28, which is adjustably mounted in the segmental slot 25 of the bracket 24. As the rocking frame 19 moves back and forth, the link 27 will 20 part to the feed bar 12, a reciprocating movement which gives to the feed dog its feeding movement. By adjusting the stud 28 in the segmental slot 25, the stroke of the main feed dog may be varied.

25 The auxiliary feed dog 29 is located above the work support, and engages the material entirely at one side of the needle, as shown in Fig. 7. Said auxiliary feed dog is also located so as to engage the material in advance of the needle, so that the material or fabric will be fed up to the stitching point. The auxiliary feed dog is formed on the end of an arm 30, which in the rear of the needle extends laterally across the line of feed, and 30 thence downwardly, where it is connected to the auxiliary feed bar 31, (see Figs. 5 and 6). Said arm 30 is secured to the auxiliary feed bar by means of a screw 32, and an adjustable stop screw 33 serves to position the auxiliary feed dog relative to the auxiliary feed bar.

The auxiliary feed bar as herein shown, rests at its forward end on an eccentric 34, mounted on the main shaft 14. The auxiliary feed bar also carries a spring arm 35, which extends underneath the main shaft 14, and carries a bearing plate coöperating with the eccentric 34. It will thus be seen that the auxiliary feed bar will be positively 45 raised and lowered by means of the eccentric 34, although if desired said auxiliary feed bar may be raised off from the eccentric, as the spring arm 35 will yield to allow such movement. The auxiliary feed bar at 50 its rear end is pivoted at 36 to a rock lever 37, which in turn is pivotally supported at 38 by the rocking frame 19. The rock lever 37 is pivotally connected to a link 39, which at its other end engages a short arm 40 of a 55 rock shaft 41, which is pivotally supported by the fulcrum pin of the rocking frame 19. The arm 42 of the rock shaft 41 is provided with an eye 43. A chain or a rod or any other suitable connection may be attached to 60 the eye 43 at one end, and at its other end

to a treadle, whereby the rock shaft 41 may be readily swung about its axis whenever desired by the operator. Instead of connecting the arm 42 to a treadle, said arm may be connected to a knee shift, or any other 70 suitable operating mechanism.

A spring 44 engages the under face of the arm 42, and normally holds said arm in raised position. A stop screw 45 passing through the arm 42, limits the upward 75 movement of said arm. When the arm 42 is in raised position, the link 39 will throw upward the outer end of the rock lever 37, which, swinging about the pivot 38, will throw downward the pivotal connection 36 80 between the rock lever 37 and the auxiliary feed bar 31. This downward movement of the auxiliary feed bar swings the auxiliary feed bar about the supporting eccentric 34 as an axis, and lifts the auxiliary feed dog 85 off from the fabric, so that the reciprocating movements and the up and down movements of the auxiliary feed dog do not cause the feed dog to engage the fabric, and, therefore, said feed dog is ineffective. If, however, the arm 42 be thrown downward, as shown in Fig. 6, the rock lever 37 would be oscillated in the opposite direction, lifting the pivotal connection 36 between the rock lever and auxiliary feed bar, which will 90 swing the auxiliary feed dog into position, so as to contact with the fabric or material, and thus become effective in the feeding operation.

It will readily be seen that the auxiliary 10 feed bar may be shifted from effective to ineffective position, during the operation of the machine. It will also be seen that the spring 44 normally holds the auxiliary feed dog out of contact with the material, and when an operator desires to secure the function of the auxiliary feed dog, the lever 42 is depressed. As soon as the lever is released, the spring will cause the same to at once return to the position shown in Fig. 5, 11 thus rendering the auxiliary feed dog ineffective.

To steady the auxiliary feed dog, I have provided a bracket 46, which is secured to the auxiliary feed bar by a suitable screw. 11 Said bracket carries a laterally projecting member 47, which has spaced arms 48, 48, between which the main feed bar reciprocates. The rock lever 37 has an extended sleeve 48^a, and the main feed bar reciprocates in a space between the end of the sleeve 48^a and the collar 49, forming a part of the 12 rocking frame 19.

Inasmuch as the auxiliary feed bar is pivoted directly to the rock lever 37, which in turn is supported by the rocking frame 19, it will be seen that the auxiliary feed bar will be reciprocated back and forth by the movements of the rocking frame 19, and that the extent of movement of the auxiliary 13

feed dog will depend upon the extent of oscillation of the pivotal support 38 for the rock lever 37.

Inasmuch as the pivotal support 38 is a greater distance from the axis of the rocking frame 19 than the pivotal connection between the link 27 and the bracket 34, the auxiliary feed dog will be given a greater movement than the main feed dog. When it is desired to adjust the extent of movement of the auxiliary feed dog, the crank pin 22 is shifted in the slot in the crank disk 23, so as to increase the oscillation of the rocking frame 19. The extent of movement of the main feed dog may be independently adjusted by varying the position of the stud 28 in the segmental slot 25.

The main feed dog 11 is provided with a forwardly projecting smooth portion 50, which is located directly underneath the teeth of the auxiliary feed bar when said auxiliary feed bar is in effective position, and said smooth portion of the main feed dog will assist the auxiliary feed dog in clamping the fabric to move the same, although said smooth portion will in no way retard a faster movement of the fabric at the point engaged by the auxiliary feed dog, than at the point engaged by the main feed dog.

Having thus described my invention, what I claim as new and desire to secure by Letters Patent, is:

1. The combination of a work support, stitch forming mechanism and feeding mechanism, said feeding mechanism including a main feeding member and an auxiliary feeding member, means for moving said auxiliary feeding member back and forth to feed the material and up and down out of and into engagement with the material, said auxiliary feeding member having a differential movement relative to the main feeding member, means for normally holding said auxiliary feeding member out of effective engagement with the fabric, and means whereby the auxiliary feeding member may be moved into effective engagement with the fabric, without stopping the stitch forming mechanism.

2. The combination of a work support, stitch-forming mechanism and feeding mechanism including an auxiliary feed bar located beneath the work support, an auxiliary feed dog rigidly carried thereby, means for moving the auxiliary feed bar back and forth and up and down, and means whereby said auxiliary feed dog may be moved out of operative engagement with the fabric without stopping the feeding action of the main feeding mechanism and without stopping the stitch-forming mechanism.

3. The combination of a work support, stitch-forming mechanism and feeding mechanism, including a main feeding member, an

auxiliary feed bar located beneath the work support, an auxiliary feed dog rigidly carried thereby, means for giving the auxiliary feed dog a differential movement relative to the main feed member, means for normally holding said auxiliary feed dog out of effective engagement with the fabric, and means for moving said auxiliary feed dog into effective engagement with the fabric, without stopping the stitch-forming mechanism. 75

4. The combination of a work support, stitch-forming mechanism and feeding mechanism, including a main feeding member, an auxiliary feed bar located beneath the work support, an auxiliary feed dog rigidly carried by said auxiliary feed bar and extending above the work support, so as to engage the upper surface of the fabric, and means for moving said auxiliary feed dog into and out of operative engagement with the fabric 85 without stopping the feeding action of the main feeding member and without stopping the stitch-forming mechanism. 80

5. The combination of a work support, stitch-forming mechanism and a feeding mechanism, including an auxiliary feed bar, an auxiliary feed dog rigidly carried by said feed bar, and means for swinging said auxiliary feed bar, so as to render said auxiliary feed dog effective or ineffective, without stopping the feeding action of the main feeding mechanism and without stopping the stitch-forming mechanism. 95

6. The combination of a work support, stitch-forming mechanism and feeding mechanism, including an auxiliary feed bar, an auxiliary feed dog rigidly carried thereby and extending above the work support, so as to engage the upper surface of the fabric, and means for swinging said auxiliary feed bar 100 105 so as to render said auxiliary feed dog effective or ineffective, without stopping the feeding action of the main feeding mechanism and without stopping the stitch-forming mechanism. 110

7. The combination of a work support, stitch-forming mechanism and feeding mechanism, including an auxiliary feed bar, an auxiliary feed dog rigidly carried by said feed bar, means for normally swinging said auxiliary feed bar so that said auxiliary feed dog is ineffective, and means under the control of the operator for swinging said auxiliary feed bar so as to render said auxiliary feed dog effective, without stopping the feeding action of the main feeding mechanism and without stopping the stitch-forming mechanism. 115 120

8. The combination of a main feed bar, a rocking frame, means for slidably connecting one end of said main feed bar to said rocking frame, means for raising and lowering the other end of said main feed bar, independent means operated from said rocking frame for reciprocating said main feed 125 130

- 4
- bar, an auxiliary feed bar, an auxiliary feed dog carried thereby, and means for reciprocating said auxiliary feed bar from said rocking frame.
5. The combination of a main feed bar, a rocking frame, means for slidably connecting one end of said main feed bar to said rocking frame, means for raising and lowering the other end of said main feed bar, said rocking frame having a laterally projecting bracket provided with a segmental slot, a link connecting said main feed bar with the slot in said bracket, an auxiliary feed bar, an auxiliary feed dog carried thereby, and means for reciprocating said auxiliary feed bar from said rocking frame.
10. The combination of a main feed bar, a main feed dog carried thereby, a main shaft, an eccentric carried by said main shaft for raising and lowering said feed bar, a rocking frame, means for slidably connecting said main feed bar to said eccentric and to said rocking frame, and means for reciprocating said main feed bar.
15. The combination of a main feed bar, a main feed dog carried thereby, a main shaft, an eccentric carried by said main shaft for raising and lowering said feed bar, a rocking frame, means for slidably connecting said main feed bar to said eccentric and to said rocking frame, said rocking frame carrying a projecting bracket having a segmental slot therein, and a link for connecting the main feed bar to the segmental slot in said bracket.
20. The combination with a main feed bar, a feed dog carried thereby, means for supporting and reciprocating said main feed bar, an auxiliary feed bar, an auxiliary feed dog carried thereby, independent means for engaging and supporting said auxiliary feed bar, and means for slidably connecting the main feed bar and the auxiliary feed bar, whereby said auxiliary feed bar may be moved longitudinally of the main feed bar, said last named means including devices to prevent lateral movement of one feed bar relative to the other.
25. The combination with a main feed bar, a feed dog carried thereby, means for supporting and reciprocating said main feed bar, an auxiliary feed bar, an auxiliary feed dog carried thereby, independent means for engaging and supporting said auxiliary feed bar, and a bracket carried by said auxiliary feed bar and having spaced arms between which said main feed bar reciprocates.
30. The combination of a work support, a main feed bar, a feed dog carried thereby, a rocking frame, an auxiliary feed bar, means for connecting said auxiliary feed bar to said rocking frame, a feed dog carried by said auxiliary feed bar, means for slidably connecting said main feed bar to the rocking
- frame, means for reciprocating said auxiliary feed bar from the rocking frame, and independent means connecting the main feed bar to the rocking frame at a different point beneath the work support from the connection to the auxiliary feed bar, whereby said feed bars are given a differential movement relative to each other.
35. The combination of a work support and stitch-forming mechanism, of a feeding mechanism including a main feed, an auxiliary feed bar, a rocking frame, means for reciprocating said main feed bar from said rocking frame, means for giving said auxiliary feed bar a differential movement from said rocking frame, a feed dog carried by said auxiliary feed bar, and means for rendering the feeding movements of said auxiliary feed dog ineffective, without stopping the feeding action of the main feeding mechanism and without stopping the stitch-forming mechanism.
40. The combination of a feed bar, means for reciprocating said feed bar, a feed dog carried by said feed bar, means for raising and lowering said feed bar, and means for swinging said feed bar, for rendering said feed dog effective or ineffective, including a rock lever, and a stop for limiting the movement of said rock lever.
45. The combination of an auxiliary feed bar, a feed dog carried thereby, a rock lever for rendering the movements of said auxiliary feed dog effective or ineffective, a spring operating upon said rock lever for holding said auxiliary feed dog in ineffective position, a stop for limiting the movement of said rock lever, and means for rocking said lever to render the feed dog effective.
50. In a sewing machine, a feeding mechanism including a main feeding member, means for reciprocating said main feeding member, an auxiliary feeding member cooperating with said main feeding member to feed the fabric, said main feeding member carrying a feed dog having a serrated and a smooth portion, said auxiliary feeding member being disposed so as to engage the material directly above the smooth portion of said main feeding member, and means for moving the auxiliary feeding member faster than said main feeding member.
55. In a sewing machine, a feeding mechanism including a main feeding member, means for reciprocating said main feeding member, an auxiliary feeding member cooperating with said main feeding member to feed the fabric, said main feeding member carrying a feed dog having a serrated and a smooth portion, said auxiliary feeding member being disposed so as to engage the material directly above the smooth portion of said main feeding member, and means for moving the auxiliary feeding member faster than said main feeding member, said
60. The combination of a work support, a main feed bar, a feed dog carried thereby, a rocking frame, an auxiliary feed bar, means for connecting said auxiliary feed bar to said rocking frame, a feed dog carried by said auxiliary feed bar, means for slidably connecting said main feed bar to the rocking
65. The combination of a work support, a main feed bar, a feed dog carried thereby, a rocking frame, an auxiliary feed bar, means for connecting said auxiliary feed bar to said rocking frame, a feed dog carried by said auxiliary feed bar, means for slidably connecting said main feed bar to the rocking
70. The combination of a work support and stitch-forming mechanism, of a feeding mechanism including a main feed, an auxiliary feed bar, a rocking frame, means for reciprocating said main feed bar from said rocking frame, means for giving said auxiliary feed bar a differential movement from said rocking frame, a feed dog carried by said auxiliary feed bar, and means for rendering the feeding movements of said auxiliary feed dog ineffective, without stopping the feeding action of the main feeding mechanism and without stopping the stitch-forming mechanism.
75. The combination of a work support and stitch-forming mechanism, of a feeding mechanism including a main feed, an auxiliary feed bar, a rocking frame, means for reciprocating said main feed bar from said rocking frame, means for giving said auxiliary feed bar a differential movement from said rocking frame, a feed dog carried by said auxiliary feed bar, and means for rendering the feeding movements of said auxiliary feed dog ineffective, without stopping the feeding action of the main feeding mechanism and without stopping the stitch-forming mechanism.
80. The combination of a feed bar, means for reciprocating said feed bar, a feed dog carried by said feed bar, means for raising and lowering said feed bar, and means for swinging said feed bar, for rendering said feed dog effective or ineffective, including a rock lever, and a stop for limiting the movement of said rock lever.
85. The combination of an auxiliary feed bar, a feed dog carried thereby, a rock lever for rendering the movements of said auxiliary feed dog effective or ineffective, a spring operating upon said rock lever for holding said auxiliary feed dog in ineffective position, a stop for limiting the movement of said rock lever, and means for rocking said lever to render the feed dog effective.
90. The combination of a feed bar, means for reciprocating said feed bar, a feed dog carried by said feed bar, means for raising and lowering said feed bar, and means for swinging said feed bar, for rendering said feed dog effective or ineffective, including a rock lever, and a stop for limiting the movement of said rock lever.
95. The combination of a feed bar, means for reciprocating said feed bar, a feed dog carried by said feed bar, means for raising and lowering said feed bar, and means for swinging said feed bar, for rendering said feed dog effective or ineffective, including a rock lever, and a stop for limiting the movement of said rock lever.
100. The combination of an auxiliary feed bar, a feed dog carried thereby, a rock lever for rendering the movements of said auxiliary feed dog effective or ineffective, a spring operating upon said rock lever for holding said auxiliary feed dog in ineffective position, a stop for limiting the movement of said rock lever, and means for rocking said lever to render the feed dog effective.
105. The combination of a feed bar, means for reciprocating said feed bar, a feed dog carried by said feed bar, means for raising and lowering said feed bar, and means for swinging said feed bar, for rendering said feed dog effective or ineffective, including a rock lever, and a stop for limiting the movement of said rock lever.
110. The combination of a feed bar, means for reciprocating said feed bar, a feed dog carried by said feed bar, means for raising and lowering said feed bar, and means for swinging said feed bar, for rendering said feed dog effective or ineffective, including a rock lever, and a stop for limiting the movement of said rock lever.
115. The combination of a feed bar, means for reciprocating said feed bar, a feed dog carried by said feed bar, means for raising and lowering said feed bar, and means for swinging said feed bar, for rendering said feed dog effective or ineffective, including a rock lever, and a stop for limiting the movement of said rock lever.
120. The combination of a feed bar, means for reciprocating said feed bar, a feed dog carried by said feed bar, means for raising and lowering said feed bar, and means for swinging said feed bar, for rendering said feed dog effective or ineffective, including a rock lever, and a stop for limiting the movement of said rock lever.
125. The combination of a feed bar, means for reciprocating said feed bar, a feed dog carried by said feed bar, means for raising and lowering said feed bar, and means for swinging said feed bar, for rendering said feed dog effective or ineffective, including a rock lever, and a stop for limiting the movement of said rock lever.
130. The combination of a feed bar, means for reciprocating said feed bar, a feed dog carried by said feed bar, means for raising and lowering said feed bar, and means for swinging said feed bar, for rendering said feed dog effective or ineffective, including a rock lever, and a stop for limiting the movement of said rock lever.

auxiliary feeding member and said smooth portion of the main feed dog being located in front of the serrated portion of said main feed dog.

5 20. A sewing machine including a main feeding mechanism and an auxiliary feeding mechanism, said main feeding mechanism having a main feed dog provided with a serrated and a smooth portion, said auxiliary

feeding mechanism having a feeding member cooperating with the smooth portion of said main feed dog. 10

In testimony whereof I affix my signature, in presence of two witnesses.

WARD E. WRIGHT.
